JOSEPH ERNEST COLAS, OF PARIS, FRANCE.

INDICATING, REGISTERING, AND CONTROLLING DEVICE WORKED BY AN ELECTRIC CURRENT.

1,124,864.

Specification of Letters Patent.

Patented Jan. 12, 1915.

Application filed January 11, 1910. Serial No. 537,545.

To all whom it may concern:

Be it known that I, JOSEPH ERNEST COLAS, citizen of France, residing at Paris, France, have invented new and useful Improvements 5 in the Indicating, Registering, and Controlling Devices Worked by an Electric Current, (for which I have filed a patent in France No. 398,465, bearing date January 13, 1909,) of which the following is a specification.

The present invention has for its object an electro-mechanical device which enables indicating signaling or registering apparatus, placed upon the locomotive or upon a car of 15 the train, to be operated by means of induced currents produced by magneto-electric machines of any type.

According to the present invention the magneto-electric machine is mounted on the 20 locomotive preferably, or on any car of the train, in such manner that its armature is forcibly rotated in one direction as a consequence of the encounter of a pendant lever, acting upon the said armature, with a projecting block arranged upon the track at any 25 desired place, the said armature being rotated in the other direction by means of an antagonistic spring, which thus generates two electric currents of opposite direction 30 which can be utilized in any suitable manner to actuate the apparatus to be utilized. In addition the induced currents produced as described above, can, in accordance with the device which forms the subject matter 35 of the present invention, be delivered, or intercepted, by means of a circuit-breaker, also mounted on the locomotive or on any car of the train, the said circuit-breaker being controlled by a pendant lever and a projecting 40 block arranged upon the track, in such a position, in relation to the projecting block causing the operation of the magneto, that the current produced by this latter is only distributed at suitable moments to the apparatus 45 to be utilized.

Although the circuit-breaker specified above does not constitute an indispensable element of the device which forms the subject matter of the present invention, it is evident 50 that it permits of obtaining a coefficient of safety thanks to which if any obstacle produces the movement of the arma-

ture of the magneto at any point not corresponding to one of the points determined upon for the operation of the apparatus utilizing the electric current thus produced, this apparatus does not operate, the circuit-breaker not having been placed in a position suitable for this operation.

Figure 1 is a view of the current generating portion of my device, and Fig. 2 is a view showing the relation of the circuit breaker to the generator. Fig. 3 is a diagrammatic view of the entire system arranged upon the chassis of the locomotive, 60 parts being omitted.

The same numerals indicate like parts in all the figures.

In these figures, 1, designates the magneto-electric machine, and 2 the magnets of the 70 said machine, which is mounted on the chassis L of the locomotive. On the shaft 3 of the armature is keyed an elbow lever 4, one arm 6 of which is controlled by a spring 5 fixed at its one end to the extremity of the said 75 arm 6, and at its opposite end to a fixed point 7. The other arm of the lever 4 carries a roller 8, which is mounted on an axis 9, and which is designed to coact with a cam 10, keyed to an axis 11 furnished with a lever 12. The cam 10 is controlled by two draw springs 13 and 14, fixed, respectively, at one of their ends to the said cam at 15 and 16, and at their other ends to a fixed point 17. A stud 18 co-acts with the lever 80 12 so as to cause this latter to oscillate through a certain angle, and is placed on the road bed or track V at a point corresponding to the moment at which the apparatus actuated by the electric current supplied by 85 the magneto-electric machine 1 is to come into operation.

The terminal 19 of the collector 20 of the magneto is connected by a conductor 21 to the brush 22 of a commutator constituted by 90 a disk or sector 23 keyed on a shaft 24 suitably mounted on the chassis L of the locomotive, in order to be able to oscillate under the action of an oscillating lever 25 keyed on the said shaft A. This disk carries an insulating sector 26, which is normally in contact with the brush 22, and a conducting sector 27 which is always in contact with a brush 28. The disk 23 is controlled by two 100

draw springs 29, 30, fixed at one of their ends to the said disk at 31 and 32, and at the other of their ends to a fixed point 33. The brush 28 is connected by a conductor 34 to the apparatus 35 which is to be operated, and the lever 25 co-acts with a striker or stud 36 placed on the track V at a point corresponding to the moment when the said apparatus should come into operation by 10 means of the current produced at the same moment by the magneto-electric machine 1. It will be seen that by this mode of construction upon the lever 12 encountering the striker or stud 18, the cam 10 will turn 15 through a certain angle x , and it is easy to foresee that the respective arrangements of the lever and striker can be so determined that this angle x rotates the cam 10 to such a degree as to raise the roller 8 sufficiently to 20 make it bear on the rise of the said cam. The displacement of the roller 8 naturally causes a displacement through an angle β of the arm 6 of the lever 4, and consequently 25 the tightening of the spring, as well as a displacement of the armature of magneto.

When the lever 12 is released from the striker or stud 18, the cam returns, under the influence of the springs 13, 14, to the normal position shown on the drawings, that 30 is to say to a position in which it presents its hollow part to the roller 8, whereupon the latter immediately returns to its normal position, thus influencing, through the lever 4, the armature of the magneto, and effecting 35 thus the production of an electric current. This current is collected at 19 and flows to the apparatus 35 upon the circuit 21, 22, 27, 28, 34 being closed, as is the case where an interrupter is employed, as shown 40 in the drawings, between the magneto and the apparatus to be operated, when the pendant 25 having been displaced by the projecting block 36, the conductor 27 of the interrupter 23 is brought into contact with 45 the brush 22, thus connecting the two brushes 22 and 28, the position of the projecting block 36 on the road being otherwise such that it acts upon the pendant 25 a little before the projecting block 18 acts upon the 50 pendant 12, and leaves the said pendant 25 a little after the projecting block 18 has left the pendant 12.

The shape of the cam 10, and the arrangement of the interrupter 23, permit of the 55 working of the apparatus in either direction, that is to say whether the vehicle moves in the direction shown by the arrow D, or in the opposite direction.

As may be seen, in the particular case of 60 the working of railways, the present improvements are applicable either to apparatus placed on the vehicles and designed to register or to indicate various peculiarities of the road, or to produce at predetermined

points of the journey predetermined actions 65 on the vehicles, such as applying the brakes. They are also applicable to apparatus placed on the line to register the passing of a vehicle, or to indicate that it occupied a certain place along the line; such is the case, 70 for instance, with disks, semaphores, block-systems, etc., the automatic working and disengagement of which will be very much improved by the application thereto of the present invention. The application of these 75 improvements is not, however, limited to the examples hereinbefore mentioned, as it is practicable in any case where indicating, registering, and controlling devices worked by an electric current are concerned. 80

Having thus fully illustrated and described my invention, what I claim is:

1. In an electro-mechanical device for operating, by means of induced currents, electric apparatus placed on the locomotive of 85 a train, the combination of a magneto-electric machine placed upon the locomotive, in order to furnish the currents operating the said apparatus; projections disposed at determined points along the track; a pendent 90 lever adapted to engage said projections and be rocked thereby as the locomotive passes the projections; an armature lever keyed to the armature shaft of the magneto and adapted to be moved in one direction by the 95 pendent lever whereby the armature is turned in one direction; and a retractor for causing the armature to turn in the opposite direction for producing said induced currents. 100

2. In an electro-mechanical device for operating, by means of induced currents, electric apparatus placed on the locomotive of 105 a train, the combination of a magneto-electric machine placed upon the locomotive, in order to furnish the currents operating the said apparatus; projections disposed at determined points along the track, a pendent lever adapted to engage said projections and be rocked thereby as the locomotive passes 110 the projections; an armature lever keyed to the armature shaft of the magneto and adapted to be moved in one direction by the pendent lever whereby the armature is turned in one direction; a retractor for 115 causing the armature to turn in the opposite direction for producing said induced currents; conductors forming a circuit between said magneto-electric machine and apparatus to be operated by the currents 120 generated by the magneto; a commutator in said circuit for closing the same; a pendent lever adapted when rocked to operate said commutator; and additional projections 125 arranged along the track for rocking said last-named lever as the train passes, the relative position between the first and last-named projections being such that current

is induced and said circuit closed at the same time, whereby current can reach and operate said apparatus only at the required instant and not when the magneto might 5 be accidentally operated by any obstacle whatever placed upon the track.

In testimony whereof I have signed my

name to this specification in the presence of two subscribing witnesses.

JOSEPH ERNEST COLAS.
